CLAIM

The ornamental design for a control panel for an engine operated generator, as shown and described.

DESCRIPTION

FIG. 1 is a perspective view of a control panel for an engine operated generator showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken lines shown are for the purpose of illustrating environmental features and form no part of the claimed design.
